LENS TURRET FOR CAMERAS

Otto Wittel and Donald G. Haefele, Rochester, N. Y.,
assignors to Eastman Kodak Company, Rochester,
N. Y., a corporation of New Jersey

Application April 18, 1955, Serial No. 35,563

Term of patent 14 years

(Cl. D61—1)

Fig. 1

Fig. 2

Fig. 3

Fig. 4

Fig. 1 is a perspective view of the lens turret showing our new design;

Fig. 2 is a side elevation of the lens turret shown in Fig. 1;

Fig. 3 is a front plan view of the lens turret shown in Fig. 1; and

Fig. 4 is a top plan view of the lens turret shown in the preceding figures.

We claim:

The ornamental design for a lens turret for cameras, as shown.
